Primary Examiner — Sheryl Lane*Assistant Examiner* — Leisha Price(74) Attorney, Agent, or Firm — Amster, Rothstein & Ebenstein LLP(57) CLAIM

The ornamental design for a binder, as shown and described.

DESCRIPTION

FIG. 1 is an isometric view of a binder according to the present invention;

FIG. 2 is a plan view of the interior of the binder shown in FIG. 1 in an open configuration;

FIG. 3 is a side view of the binder of FIG. 1;

FIG. 4 is a side view of the spine of the binder of FIG. 1;

FIG. 5 is an interior side view of the binder of FIG. 1 in a partially closed position; and,

FIG. 6 is a bottom side view of the binder of FIG. 1 in a partially closed position.

The broken lines in the drawings illustrate portions of the binder which form no part of the claimed design.

1 Claim, 4 Drawing Sheets(56)
